(57) **CLAIM**

The ornamental design for a shrink wrapped egg stack, as shown and described.

DESCRIPTION

FIG. 1 is a perspective view of a shrink wrapped egg stack showing my new design;

FIG. 2 is a top plan view of the shrink wrapped egg stack; FIG. 3 is a bottom plan view of the shrink wrapped egg stack;

FIG. 4 is a front side elevational view of the shrink wrapped egg stack;

FIG. 5 is a back side elevational view of the shrink wrapped egg stack;

FIG. 6 is a right side elevational view of the shrink wrapped egg stack; and,

FIG. 7 is a left side elevational view of the shrink wrapped egg stack.

The broken lines and the areas enclosed by them in FIGS. 1, 3, 5, and 6 are for illustrative purposes only and form no part of the claimed design.

1 Claim, 7 Drawing Sheets

FIG. 1

FIG. 2

- Keep eggs refrigerated—do not freeze.
- Store eggs away from strong odors.
- Wash hands.
- Use only clean, uncracked eggs.
- Use clean, sanitized utensils and equipment.
- Cook eggs thoroughly.
- Hold cold egg dishes below 40°F.
- Hold hot egg dishes above 140°F.
- Never leave egg dishes at room temperature for more than one hour (including preparation and service).
